UNITED STATES PATENT OFFICE.

JOHN P. WEIS, OF NYACK, NEW YORK, ASSIGNEE TO LUCIUS N. LITTAUER, OF GLOVERSVILLE, NEW YORK.

SEWING-MACHINE.

1,222,339.

Specification of Letters Patent. Patented Apr. 10, 1917.

Application filed August 5, 1916. Serial No. 113,222.

To all whom it may concern:

Be it known that I, JOHN P. WEIS, a citizen of the United States, residing at Nyack, in the county of Rockland and State of New York, have invented certain new and useful Improvements in Sewing-Machines, of which the following is a specification.

This invention relates to sewing machines, and more particularly to that class of machines used for stitching inner soles of shoes, the object of the invention being to provide an improved machine for stitching a strip of canvas to one side of the inner sole along the edges thereof, and while this improved machine may be used for a wide variety of work it is in the present instance shown especially organized for the stitching to insoles of fiber of a reinforced canvas strip or tape in such a way that a rib of the canvas remains upstanding for the attachment of the shoe upper.

In the drawings accompanying and forming part of this specification, Figure 1 is a front elevation of the machine; Fig. 2 is a top plan view of the machine, showing the three positions of the work guide controlling handle; Fig. 3 is an end view showing the stitching and feeding mechanisms and an inner sole in position to complete the stitching of the canvas tape thereto; Fig. 4 is a right-hand view of the top feed and presser mechanism looking in the direction of the arrow in Fig. 1; Fig. 5 is a perspective view of the underside of the cloth plate showing the work guide in full lines and the cloth and throat plates in dotted lines; Fig. 6 is a top view of the throat plate; Fig. 7 is a sectional view showing the manner in which the canvas tape is folded and stitched ready to be stitched by this improved machine to the fiber board inner sole; Fig. 8 is an end and top view of the bottom feed dog; Fig. 9 is a front view showing details of the top feed and presser finger in position to feed the work; Fig. 10 is a view similar to Fig. 9, showing the parts in position when the needles are in the work and the presser finger holding the work against movement while the top feed is moving forward for the next feed movement; Fig. 11 is a detail sectional view of the top feed and presser finger actuating connection; and Fig. 12 is a detail view of the fiber board inner sole with a canvas tape stitched thereto.

Similar characters of reference indicate

corresponding parts in the several figures of the drawings.

In the preferred form thereof herein shown and described the machine base 1 carries the trunk 2 of the machine and the hollow overhanging arm 3 terminating in a head 4, in which the needle bar reciprocates. A rotary shaft 6 is mounted in the machine base and is supported by suitable bearings. Connections, (not shown), but such as are usual in Metropolitan sewing machines, extend from the bottom shaft crank pins and coöperate with similar crank pins carried by a top shaft 8, which is also mounted in suitable bearings carried by the hollow arm, and on this top shaft is secured a combined belt and hand wheel 5. Secured to the lower shaft 6 is an eccentric 9, which operates the connection 10 which has an end 11 connected by a shoulder screw 12 to an arm 13. This arm 13 is secured to the looper shaft 14 mounted in suitable bearings 15 of a looper bracket 16 secured to the base 1. Looper holders 17 are secured to the looper shaft 14 and carry suitable loopers 18 to coöperate with the needles 19 carried by the needle bar 20, which works in bearings 2 formed as a part of the head 4. The needle bar is reciprocated by a pitman 23 connected with it and with a crank pin 24 carried by a disk 25 secured to the top shaft 8, and this gives the required motion to the needle bar, which is timed so as to coöperate with the loopers 18 to make the stitches.

The bottom feed mechanism comprises a rocker frame 26 pivoted as at 27 to the base 1, and the upper end thereof carries a pin 28 for movement therewith. A pitman connection 29 connects this pin 28 with the usual adjustable crank 30 for regulating the length of movement of the feed 31. The feed is secured as at 32 to a feed bar 33, which carries an extended plate 34 to coöperate with the feed lifter eccentric 35, also secured to the shaft 6 for rotary movement therewith. A bottom plate 36 attached to the feed bar limits the upward movement of the feed bar so that its action is positive at high speed. The feed bar has its rear end 37 journaled on the pin 28 of the rocker frame 26 so that it is actuated by such rocker frame.

It is to be particularly observed that the peculiar construction of this bottom feed mechanism is such that nearly all of its

working parts are located in front toward the operator and to the right of the needles to provide free access or working space at the starting position and facilitate the turning of the work at high speed so as not to interfere with the rib of the canvas tape when making the sharp turns at the top of the inner sole. It will be seen that the rib of the canvas tape extends down into and below the surface of the work plate of the machine and that the feed dog 31 is provided with a slot 38 for the reception of the rib 39 of such canvas tape.

The construction of this tape (see Fig. 7) 15 comprises a flared portion 40, a portion 41 bent at right angles thereto and then bent into U-shaped form as at 42, with an outwardly bent portion 43 and a bent over part 44, while the edge of the tape is curved over, 20 as at 45, into the U-shaped part thereby to conceal the edge 46, all connected by a stitch-line 47 stitching the several portions together and holding the same in position.

The construction of the feed dog 31 (see Fig. 8) is especially adapted for this tape, 25 having a part 48 with feed teeth slightly lower than the part 49. The part 48 co-acts with the portion 40 of the tape, while the lower portion of the feed 48 co-acts with the 30 double fold of the tape 44. The difference in the height of the two sections of the feed is to meet the difference in thickness of the material to be fed, so as to have a uniform action thereon. The bottom feed operates in 35 the space 50 of the throat plate 51, (see Fig. 6), which is also provided with a slot 52 throughout its length to receive the portion 42 of the tape 39. This slot has its edges flared as at 52' for free entrance. A top 40 plate 53 is secured to the throat plate, and this plate has an opening 54 to facilitate starting the tape. The throat plate is recessed as at 55 sufficiently for the free passage of the portion 40 of the tape and is also 45 recessed as at 56 for free passage of the portion 44 of the tape underneath the top plate 53. It will be understood that to properly 50 guide the folded canvas strip it must be controlled accurately up to the point of stitching, and the construction of the parts 55 must be such as not to interfere with making the sharp turns at the front of the inner soles and that the entire feeding action must be confined very close to the position of stitching. The throat plate 51 is attached to the cloth plate by screws 57. This cloth plate 58 is also of special construction, being secured at one end to an apron 59, which is an extension of the trunk 2. The cloth plate 60 has a curved front edge 60, notched as at 61 to engage a stop finger 62 carried by a work control handle 63. Stop lugs 64 provided with adjusting screws 65 afford a means for stopping the movement of the handle 63 65 when shifted to the right or left. This han-

dle 63 is of hollow construction to receive a spring 66 which surrounds the stem of the stop finger so as to force it inwardly against the edge 60 of the cloth plate so that the handle will remain in either of the three positions shown in Fig. 2. The cloth plate 58 is bent downward as at 69 just at the needle line to have an angular portion 70 and a vertical portion 71, (see Fig. 3), which is attached to the machine base by screws 72. 70 The front end of the cloth plate is broken away in Fig. 3 to show clearly the feeding mechanism. The handle 63 has an extended portion 73 tapped to receive a shoulder screw, as at 74, which operates freely in the 80 cloth plate. A screw 75 attaches an end 73 of this handle to a slide 76, which is milled out to receive an arm 77 adjustably held therein by a screw 78. A roller 79 is carried by this arm 77 and rotates freely on 85 a stud 80 and is in position adjacent the needles to guide the edge of the work and facilitate the guiding of the curved edge of same. All of the parts connected with the handle 63 are located underneath the cloth 90 plate 58, while the roller stud 80 operating through a slot in the cloth plate (not shown) serves as a guide for the roller in its movement to and from the needles. The purpose of this roller guide is to guide the edge of 95 the fiber board inner sole in such a manner as to permit the starting of the stitching of the tape at 81, (see Fig. 12). A little way in from the edge, as the stitching proceeds, the handle 63 is gradually shifted, bringing 100 the roller 79 closer to the inside as it approaches the turn 82 and still closer as it approaches the portion 83, and then gradually moved in the opposite direction as the inner sole approaches the position 84. This 105 condition, of course, may vary to suit the requirements of the various kinds of work.

In order to feed the heavy fiber inner sole and the heavy folded canvas tape and have one move at a uniform speed with the other, 110 it is necessary to have either a needle feed or a top feed. It has been found in practice that with a two-needle machine arranged to have the needles feed the work the fiber inner soles become damaged while 115 stitching around the curves, as it will be clear that the needle stitching on the inside of the curve must work at a different speed than the needle stitching at the outside of the curve, which is the longer of the two, 120 with the result that the inside needle frequently punches holes so close together that the fiber board is weakened and impairs its strength to such an extent that it cannot be used. The resistance of making the sharp 125 turns with the needle feed machine tends also to break the needles, interferes with the stitches, and the result is damaged work. In the present improvement I have employed a very powerful top feed co-acting with the 130

bottom feed so as to clamp the materials to be stitched together and feed the same while the needles are out of the work. Feed teeth are provided on the bottom feed dog which 5 come against the canvas tape and a smooth feed foot operates on the fiber board on top so as not to mar the same in making the sharp turns. A presser finger is also employed to hold the work down. As the feed 10 foot is raising the presser finger strips the work from the needles so that a step by step motion is provided and the work can be readily turned so as to guide it freely and rapidly in a uniform manner.

15 The top feed comprises a feed foot 85 secured to a bar 86 operating in a tube 87 for vertical rise and fall. A connecting rod 88 has its upper end 90 bent at right angles for attachment to a connection 89 and extends 20 down through the tube and is connected with the bar 86 so as to lift the feed foot 85 against the action of the spring 91, (see Fig. 3). One end of this spring abuts against the bottom end of the connection 89 while the other end abuts against the top 25 end of the bar 86. The rod 88 is free to move in the bar 86, its lower end 92 being headed over to limit the downward movement of the bar 86, while the bent upper end 90 of this rod 88 operates in a slot 93 of the tube 87 to prevent axial movement of the same. The tube 87 is pivotally supported on a bracket 121 by conical screws 94 so that the tube may rock thereon. A 30 lever 95 operated by an adjustable crank 96 carried by a disk 97 mounted for rotary motion, gives substantially a rotary movement to the pin 98 and the connection 89. The end 99 of the lever 95 reciprocates in a head 100 having a T slot 101. This head 100 is carried by a rock shaft 102, (see Fig. 1), which rocks in a bearing 103 integral with the head 4. A collar 104 is secured to the rock shaft to control the end movement 45 thereof. The disk 97 is secured to a shaft 105, (see Fig. 2), which operates in bearings 106 also integral with the top arm of the machine. This shaft 105 is provided with a gear 107 in mesh with a driving gear indicated by the dotted lines 108, (see Fig. 3) secured to the top shaft 8 carrying the drive wheel 5, so that as the top shaft 8 rotates the shaft 105 will also rotate, giving motion to the disk 97 and substantially an elliptical 50 or four-motion feeding stroke to the top feed 85. Adjacent to the crank disk 97 is an eccentric 109, (see Fig. 2), secured to the shaft 105 to give movement to a connection 110, which is of tubular form, as at 111 (see Fig. 11) to receive the stem 112 of the other part 113 of this connection. A spring 114 is interposed between the shoulders of these two parts, while a screw 115 passes through a slot 116 and limits the action of 55 this spring. A pin 117 secures this connec-

tion to a rocker arm 119, which is pivoted as at 120 to a bracket 121 of the machine head 4. The forward end of this rocker arm has pivotally attached thereto, as at 122, a U-shaped plate 123, which carries the presser 70 finger 124. In order that the presser finger may have a movement parallel to the needles a second rocker arm 126 is employed, pivoted as at 127 to the U-shaped plate and to the bracket 121, as at 128.

75 From the foregoing it will be clear that the crank 96 and the eccentric 109 are so timed as to move the presser finger downward as the feed foot 85 moves upward, and vice versa. The length of stroke or action 80 of the top feed foot 85 may be regulated by adjusting the crank 96 to and from the center of the disk 97.

In the stitching of inner soles, the beginning and ending of the stitching operation 85 must start from the edge of the inner sole. The machine must be stopped, the needles and feed foot raised and the sewing thread severed to remove and replace the work.

To facilitate this I have provided a thread 90 pull off connected with the top feed foot lifter, so that the lifting of the feed foot will simultaneously therewith pull off thread from the supply to provide sufficient to insure positive stitching on the next inner 95 sole after one has been removed and another replaced in the machine. The needle threads 129 (see Fig. 2) are led from the supply to the tensions 130, then to the eyelet 131 carried by the pull-off arm 132, then 100 through the eyelet 133, to the needle bar 134, and then to the needles 19. The pull-off lever 132 is pivoted at 135 to the top arm and is provided with an extended end 136 shaped so as to co-act with a latch lever 137, 105 which is pivoted to the top arm as at 138.

The other end of this latch lever 137 is so shaped as at 139 to overhang the foot lifting lever 140, (see Figs. 1 and 2), so as to be controlled by the movement of such feed foot 110 lifter 140, and this end 139 of the latch lever is in position to rock the latch lever on its pivot 138 in the direction of the arrow (see Fig. 1). The foot lifting lever 140 is pivoted to the top arm, as at 141, having a connection, as at 142, extending downwardly, as at 143 (see Figs. 1 and 3) and connecting, as at 144, to a lever 145 carried by the pivot 128. This lever 145 has an extending portion carrying a roller 146 which co-acts with 120 an overhanging or projecting portion 147 of the top feed foot 85, (see Fig. 1), so as to lift the foot against the action of its spring 91, and also co-acts with the rocker arm 126 to lift the presser finger 125 against 125 the action of its spring 114 so as to give freedom to remove and insert the work while the needles are resting. At the same time the hook lever 137 actuates the lever 132 to measure off the proper amount of thread. 130

The spring 114 also serves to give independent pressure to the presser finger 124 on the work independently of the top feed 85.

5 I claim as my invention:

1. In a sewing machine the combination with stitching mechanism, of feeding mechanism comprising a feed consisting of a feed dog having a slot for the reception of a work rib projecting at an angle to the side portions of the work, and a pair of feeding portions at opposite sides of said slot for feeding the work at opposite sides of the rib.

- 15 2. In a sewing machine the combination with stitching mechanism, of feeding mechanism comprising a feed consisting of a feed dog having a slot for the reception of a work rib projecting at an angle to the side portions of the work, and a pair of serrated portions at opposite sides of said slot for feeding the work at opposite sides of the rib, one of said serrated portions lower than the other to accommodate different thicknesses of the work.
- 20
- 25

3. In a sewing machine, the combination with stitching mechanism, of feeding mechanism comprising a top feed consisting of a pivotally supported member, a feed foot supported thereby for shiftable movement therewith and movement relatively thereto, a lever connected with said feed foot, a rock shaft connected with one end of said lever, and a rotary shaft connected with the other end thereof for giving a four-motion elliptical movement to said feed foot.

4. In a sewing machine, the combination with stitching mechanism, of feeding mechanism comprising a top feed consisting of a 40 pivotally supported member, a spring-pressed feed foot supported thereby for shiftable movement therewith and movement relatively thereto, a lever connected with said feed foot, a rock shaft connected 45 with one end of said lever, and a rotary shaft connected with the other end thereof for giving a four-motion elliptical movement to said feed foot.

5. In a sewing machine, the combination
50 with stitching mechanism, of feeding mecha-
nism comprising an under feed consisting
of a feed dog having a slot for the recep-
tion of a rib of the work and a pair of
feeding portions, a coöperating top feed
55 comprising a pivotally supported member,
a feed foot supported thereby for shiftable
movement therewith and movement rela-
tively thereto, a lever connected with said
feed foot, a rock shaft connected with one
60 end of said lever, and a rotary shaft con-
nected with the other end thereof for giving
a four-motion elliptical movement to said
feed foot.

6. In a sewing machine, the combination of feeding mechanism with stitching mechanism, of feeding mech-

anism comprising a top feed consisting of a pivotally supported member, a feed foot supported thereby for shiftable movement therewith and movement relatively thereto, a lever connected with said feed foot, a rock shaft connected with one end of said lever, a rotary shaft connected with the other end thereof for giving a four-motion elliptical movement to said feed foot, a presser finger, supporting means therefor, a pair of rocker members pivotally connected with said supporting means and to a fixed point of support, an eccentric on said rotary shaft, and a spring connector between one of said rocker members and said eccentric, said presser finger having parallel motion with the needle. 70 75 80

7. In a sewing machine, the combination with stitching mechanism, of feeding mechanism comprising an under feed consisting of a feed dog having a slot for the reception of a rib of the work and a pair of serrated portions one lower than the other to accommodate different thicknesses of the work, a coöperating top feed comprising a pivotally supported member, a feed foot supported thereby for shiftable movement therewith and movement relatively thereto, a lever connected with said feed foot, a rock shaft connected with one end of said lever, a rotary shaft connected with the other end thereof for giving a four-motion elliptical movement to said feed foot, a presser finger, supporting means therefor, a pair of rocker members pivotally connected with said supporting means and to a fixed point of support, an eccentric on said rotary shaft, and a spring connector between one of said rocker members and said eccentric, said presser finger having parallel motion with the needle. 85
90
95
100
105

8. In a sewing machine, the combination with stitching mechanism, of feeding mechanism comprising an under feed consisting of a feed dog having a slot for the reception of a rib of the work and a pair of feeding portions at opposite sides of said slot, a top feed coöoperating therewith, a presser finger, supporting means therefor, a pair of rocker members pivotally connected with said supporting means and to a fixed point of support, a rotary shaft, an eccentric thereon, and a spring connector between said eccentric and one of said rocker members, said finger having parallel motion with the needle. 110 115 120

9. In a sewing machine, the combination 125
with stitching mechanism, of feeding mech-
anism comprising an under feed consisting
of a feed dog having a slot for the reception
of a rib of the work and a pair of feeding 125
portions, a coöperating top feed comprising
a pivotally supported member, a feed foot
supported thereby for shiftable movement
therewith and movement relatively thereto,
a lever connected with said feed foot, a rock 130

shaft connected with one end of said lever, a rotary shaft connected with the other end thereof for giving a four-motion elliptical movement to said feed foot, and a throat 5 plate having a slot extending from end to end thereof and a recess at each side thereof for the reception of the work.

10. In a sewing machine, the combination with stitching mechanism, of feeding mechanism comprising an under feed consisting of a feed dog having a slot for the reception of a rib of the work and a pair of feeding portions, a coöperating top feed comprising a pivotally supported member, a feed foot supported thereby for shiftable movement therewith and movement relatively thereto, a lever connected with said feed foot, a rock shaft connected with one end of said lever, a rotary shaft connected 20 with the other end thereof for giving a four-motion elliptical movement to said feed foot, and a throat plate having a slot extending from end to end thereof and a recess at each side thereof for the reception of the work, 25 said slot having at one end a flared portion for the entrance of the work and at the other end an opening for the under feed.

11. In a sewing machine, the combination with stitching mechanism, of feeding mechanism comprising an under feed consisting of a feed dog having a slot for the reception of a rib of the work and a pair of feeding portions, a coöperating top feed comprising a pivotally supported member, a feed foot 30 supported thereby for shiftable movement therewith and movement relatively thereto, a lever connected with said feed foot, a rock shaft connected with one end of said lever, a rotary shaft connected with the other end 35 thereof for giving a four-motion elliptical movement to said feed foot, a throat plate having a slot extending from end to end thereof and a recess at each side thereof for the reception of the work, said slot having 40 at one end a flared portion for the entrance of the work and at the other end an opening for the under feed, and a plate extending over the recesses of the throat plate.

12. In a sewing machine, the combination with stitching mechanism, of feeding mechanism comprising an under feed consisting of a feed dog having a slot for the reception of a rib of the work and a pair of feeding portions, a coöperating top feed comprising 50 a pivotally supported member, a feed foot supported thereby for shiftable movement therewith and movement relatively thereto, a lever connected with said feed foot, a rock shaft connected with one end of said lever, a rotary shaft connected with the other end 55 thereof for giving a four-motion elliptical movement to said feed foot, a throat plate having a slot extending from end to end thereof and a recess at each side thereof for the reception of the work, said slot having 60

at one end a flared portion for the entrance of the work and at the other end an opening for the under feed, a plate extending over the recesses of the throat plate, a cloth plate carrying said throat plate, and a work guide 70 carried thereby and comprising a slidingly supported roll and a handle for shifting said roll.

13. In a sewing machine, the combination with stitching mechanism, of feeding mechanism comprising an under feed consisting of a feed dog having a slot for the reception of a rib of the work and a pair of serrated portions one lower than the other to accommodate different thicknesses of the work, a coöperating top feed comprising a pivotally supported member, a feed foot supported thereby for shiftable movement therewith and movement relatively thereto, a lever connected with said feed foot, a rock shaft 80 connected with one end of said lever, a rotary shaft connected with the other end thereof for giving a four-motion elliptical movement to said feed foot, a throat plate having a slot extending from end to end 85 thereof and a recess at each side thereof for the reception of the work, said slot having at one end a flared portion for the entrance of the work and at the other end an opening 90 for the under feed, a plate extending over the recesses of the throat plate, a cloth plate carrying said throat plate, a work guide carried thereby and comprising a slidingly supported roll and a handle for shifting said roll, and means for limiting the movement of said handle in opposite directions 95 and in an intermediate position.

14. In a sewing machine, the combination of stitching mechanism, a throat plate constructed to support and guide the work, feeding mechanism comprising an under feed and an upper feed, a presser finger co-operating with the upper feed, means for operating said feeds and presser finger, a cloth plate carrying said throat plate, and a work guide carried by said cloth plate and comprising a slidingly supported roll and a handle for shifting said roll.

15. In a sewing machine, the combination of stitching mechanism, a throat plate constructed to support and guide the work, feeding mechanism comprising an under feed and an upper feed, a presser finger co-operating with the upper feed, means for operating said feeds and presser finger, a cloth plate carrying said throat plate, a work guide carried by said cloth plate and comprising a slidingly supported roll and a handle for shifting said roll, and means for limiting the movement of said handle in opposite directions and in an intermediate position.

16. In a sewing machine, the combination of stitching mechanism, a throat plate constructed to support and guide the work,

- feeding mechanism comprising an under feed and an upper feed, a presser finger co-operating with the upper feed, means for operating said feeds and presser finger, a cloth plate carrying said throat plate, a work guide carried by said cloth plate and comprising a slidingly supported roll and a handle for shifting said roll, and means for limiting the movement of said handle in opposite directions and in an intermediate position, said handle having a spring-actuated stop finger.
17. In a sewing machine, the combination of stitching mechanism, feed mechanism comprising an under feed having a slot for the reception of a portion of the work and a top feed, a presser finger co-operating with said top feed, means for operating said feeds and presser finger, and a throat plate in position to support and guide the work, said throat plate having a slot extending from end to end thereof and a recess at each side thereof.
18. In a sewing machine, the combination of stitching mechanism, feeding mechanism comprising an under feed having a slot for the reception of a portion of the work and a top feed, a presser finger co-operating with said top feed, means for operating said feeds and presser finger, and a throat plate in position to support and guide the work, said throat plate having a slot extending from end to end thereof and a recess at each side thereof, said recesses being of different dimensions.
19. In a sewing machine, the combination of stitching mechanism, feeding mechanism comprising an under feed having a slot for the reception of a portion of the work and a pair of serrated portions one lower than the other to accommodate different thicknesses of the work and a top feed, a presser finger co-operating with said top feed, means for operating said feeds and presser finger, and a throat plate in position to support and guide the work, said throat plate having a slot extending from end to end thereof and a recess at each side thereof.
20. In a sewing machine, the combination of stitching mechanism, feeding mechanism including a top feed comprising a pivotally supported tube, a feed foot supported thereby for shiftable movement therewith and movement relatively thereto, a lever connected with said feed foot, a rock shaft connected with one end of said lever, and a rotary shaft connected with the other end of said lever for giving a four-motion elliptical movement to said feed foot.
21. In a sewing machine, the combination of stitching mechanism, feed mechanism including a top feed comprising a pivotally supported tube, a feed foot supported thereby for shiftable movement therewith and movement relatively thereto, a lever connected with said feed foot, a rock shaft connected with one end of said lever, a rotary shaft connected with the other end of

- connected with said feed foot, a rock shaft connected with one end of said lever, a rotary shaft connected with the other end of said lever for giving a four-motion elliptical movement to said feed foot, and a spring within said tube and co-operating with said foot.
22. In a sewing machine, the combination of stitching mechanism, feeding mechanism including a top feed comprising a pivotally supported tube, a feed foot supported thereby for shiftable movement therewith and movement relatively thereto, a lever connected with said feed foot, a rock shaft connected with one end of said lever, a rotary shaft connected with the other end of said lever for giving a four-motion elliptical movement to said feed foot, a spring within said tube and co-operating with said foot, a presser finger, and means connecting said presser finger with said rotary shaft.
23. In a sewing machine, the combination of stitching mechanism, feeding mechanism including a top feed comprising a pivotally supported tube, a feed foot supported thereby for shiftable movement therewith and movement relatively thereto, a lever connected with said feed foot, a rock shaft connected with one end of said lever, a rotary shaft connected with the other end of said lever for giving a four-motion elliptical movement to said feed foot, a spring within said tube and co-operating with said foot, a presser finger, means connecting said presser finger with said rotary shaft, and means connecting said presser finger with a fixed point of support thereby to give the presser finger parallel motion with the needle.
24. In a sewing machine, the combination of stitching mechanism, feeding mechanism including a top feed comprising a pivotally supported tube, a feed foot supported thereby for shiftable movement therewith and movement relatively thereto, a lever connected with said feed foot, a rock shaft connected with one end of said lever, a rotary shaft connected with the other end of said lever for giving a four-motion elliptical movement to said feed foot, a presser finger, a U-shaped member carrying said finger and inclosing said tube, a pair of rocker members pivotally connected to said U-shaped member and to a fixed point of support, an eccentric connected with said rotary shaft, and a spring connector between said eccentric and one of said rocker members.
25. In a sewing machine, the combination of stitching mechanism, feeding mechanism including a top feed comprising a pivotally supported tube, a feed foot supported thereby for shiftable movement therewith and movement relatively thereto, a lever connected with said feed foot, a rock shaft connected with one end of said lever, a rotary shaft connected with the other end of

5 said lever for giving a four-motion elliptical movement to said feed foot, a presser finger, a U-shaped member carrying said finger and inclosing said tube, a pair of rocker members pivotally connected to said U-shaped member and to a fixed point of support, an eccentric connected with said rotary shaft, a spring connector between said eccentric and one of said rocker members, and means for lifting said top feed and presser finger.

10 26. In a sewing machine, the combination of stitching mechanism, feeding mechanism including a top feed comprising a pivotally supported tube, a feed foot supported thereby for shiftable movement therewith and movement relatively thereto, a lever connected with said feed foot, a rock shaft connected with one end of said lever, a rotary shaft connected with the other end of said lever for giving a four-motion elliptical movement to said feed foot, a presser finger, a U-shaped member carrying said finger and inclosing said tube, a pair of rocker members pivotally connected to said U-shaped member and to a fixed point of support, an eccentric connected with said rotary shaft, a spring connector between said eccentric and one of said rocker members, means for lifting said top feed and presser finger, and a thread pull-off connected with said lifting means.

15 27. In a sewing machine, the combination of stitching mechanism, feeding mechanism including a four motion top feed, means for lifting said top feed, and thread pull-off means connected with said top feed lifting means.

20 28. In a sewing machine, the combination of stitching mechanism, feeding mechanism including a four motion top feed, means for lifting said top feed, and thread pull-off means operatively connected with one of said last two parts and operative on the lifting of the top feed.

25 29. In a sewing machine, the combination of stitching mechanism, feeding mechanism including a top feed, means for lifting the same and comprising a lever, a thread pull-off lever, and a latch lever operatively connected with the lifting lever for actuating the thread pull-off lever on the lifting of the top feed.

30 30. In a sewing machine, the combination of stitching mechanism, feeding mechanism including a top feed, a presser finger, means for operating said top feed and presser finger, means for lifting said presser finger and top feed, and thread pull-off means operatively connected with said lifting means for operation on the lifting of the top feed and presser finger.

35 31. In a sewing machine, the combination of stitching mechanism, feeding mechanism therefor, a presser finger coöperating with

the feeding mechanism, supporting means for said presser finger, a pair of rocker arms connected with said supporting means and pivotally connected with a fixed point of support whereby the presser finger has a parallel motion with the needle, a rotary shaft, an eccentric thereon, and a spring connector between said eccentric and one of said rocker arms.

32. In a sewing machine, the combination of a rotary driving shaft, a rotary shaft operatively connected therewith at one side thereof, a rocker shaft at the other side thereof, a pivotally supported lever connected with said second rotary shaft and with said rocker shaft, a top feed, and a pivotally supported member connected with said top feed and with said lever.

33. In a sewing machine, the combination of a rotary driving shaft, a rotary shaft operatively connected therewith at one side thereof, a rocker shaft at the other side thereof, a pivotally supported lever connected with said rotary shaft and with said rocker shaft, a top feed, a pivotally supported member connected with said top feed and with said lever, and a presser finger operatively connected with said second rotary shaft.

34. In a sewing machine, the combination of a rotary driving shaft, a rotary shaft operatively connected therewith at one side thereof, a rocker shaft at the other side thereof, a pivotally supported lever connected with said rotary shaft and with said rocker shaft, a top feed, a pivotally supported member connected with said top feed and with said lever, a presser finger operatively connected with said second rotary shaft, and means for giving said presser finger parallel motion with the needle.

35. In a sewing machine, the combination of a rotary driving shaft, a rotary shaft operatively connected therewith at one side thereof, a rocker shaft at the other side thereof, a pivotally supported lever connected with said rotary shaft and with said rocker shaft, a top feed, a pivotally supported member connected with said top feed and with said lever, a presser finger operatively connected with said second rotary shaft, means for giving said presser finger parallel motion with the needle and comprising a pair of rocker members pivotally connected with said presser finger and with a fixed point of support, and a spring connector between one of said rocker members and the rotary shaft.

36. In a sewing machine, the combination of a rotary driving shaft, a rotary shaft connected therewith, a rock shaft, an oscillating lever connected with said last two shafts, a top feed comprising a pivotally supported tube, a spring-pressed feed foot having a part extending into said tube, and a con-

nectar secured to said part and extending through the tube and pivotally connected to said oscillating lever.

37. In a sewing machine, the combination of stitching mechanism, feeding mechanism, a presser finger, a rotary shaft, an eccentric thereon, rocker means pivotally connected with said presser finger and with a fixed point of support, a telescopic connector between said eccentric and said rocker means, and a spring surrounding said telescopic connector.

38. In a sewing machine, the combination of stitching mechanism, feeding mechanism comprising an under feed constructed to receive a rib of the work and different thicknesses of the work, a throat plate constructed to permit the passage of a rib of the work from end to end thereof and to receive different thicknesses of the work, a top feed, and means for operating said feeds.

39. In a sewing machine, the combination of stitching mechanism, feeding mechanism comprising an under feed constructed to receive a rib of the work and different thicknesses of the work, a throat plate constructed to permit the passage of a rib of the work from end to end thereof and to receive different thicknesses of the work, a top feed, means for operating said feeds, a presser finger coöperating with said top feed, and means for operating it.

40. In a sewing machine, the combination of stitching mechanism, feeding mechanism comprising an under feed constructed to receive a rib of the work and feed the work at both sides of the rib, a throat plate constructed to permit the passage of a rib of the work from end to end thereof, a top feed, means for operating said feeds, a presser finger coöperating with said top feed, and means for operating it, the means for operating the top feed consisting of a pair of connected rotary shafts, a rock shaft, a lever connecting one of said rotary shafts and rock shaft, and a pivotally supported member between the top feed and said lever.

41. In a sewing machine, the combination of stitching mechanism, feeding mechanism comprising an under feed constructed to receive a rib of the work and different thicknesses of the work, a throat plate constructed to permit the passage of a rib of the work from end to end thereof and to receive different thicknesses of the work, a top feed, means for operating said feeds, a presser finger coöperating with said top feed, and means for operating it, the means for operating the top feed consisting of a pair of connected rotary shafts, a rock shaft, a lever connecting one of said rotary shafts and rock shaft, and a pivotally supported member between the top feed and said lever, and the means for operating the presser finger consisting of an eccentric carried by one of

said rotary shafts, a pair of rocker members pivotally connected with the presser finger and with a fixed point of support, and a spring connector between said eccentric and one of said rocker members.

42. In a sewing machine, the combination of stitching mechanism, feeding mechanism comprising an under feed constructed to receive a rib of the work and different thicknesses of the work, a throat plate constructed to permit the passage of a rib of the work from end to end thereof and to receive different thicknesses of the work, a top feed, means for operating said feeds, a presser finger coöperating with said top feed, means for operating it, the means for operating the top feed consisting of a pair of connected rotary shafts, a rock shaft, a lever connecting one of said rotary shafts and rock shaft and a pivotally supported member between the top feed and said lever, the means for operating the presser finger consisting of an eccentric carried by one of said rotary shafts, a pair of rocker members pivotally connected with the presser finger and with a fixed point of support and a spring connector between said eccentric and one of said rocker members, means for lifting said top feed and presser finger, and means coöperating therewith for pulling off additional thread on the lifting of said top feed and presser finger.

43. In a sewing machine, the combination of stitching mechanism, feeding mechanism comprising an under feed constructed to receive a rib of the work and different thicknesses of the work, a throat plate constructed to permit the passage of a rib of the work from end to end thereof and to receive different thicknesses of the work, a top feed, means for operating said feeds, a presser finger coöperating with said top feed, means for operating it, the means for operating the top feed consisting of a pair of connected rotary shafts, a rock shaft, a lever connecting one of said rotary shafts and rock shaft and a pivotally supported member between the top feed and said lever, the means for operating the presser finger consisting of an eccentric carried by one of said rotary shafts, a pair of rocker members pivotally connected with the presser finger and with a fixed point of support and a spring connector between said eccentric and one of said rocker members, means for lifting said top feed and presser finger, means coöperating therewith for pulling off additional thread on the lifting of said top feed and presser finger, and means for guiding the work and comprising a manually operated shiftable roller.

44. In a sewing machine the combination of stitching mechanism, feeding mechanism comprising an underfeed constructed to receive a rib of the work and feed the work

at both sides of the rib, a throat plate constructed to permit the passage of the rib of the work from end to end thereof and to receive both sides of the work, a top feed, 5 and means for operating said feeds.

45. In a sewing machine the combination of stitching mechanism, feeding mechanism comprising an underfeed constructed to receive a rib of the work and feed the work

10 at both sides of the rib, a throat plate constructed to permit the passage of the rib of the work from end to end thereof and to receive both sides of the work, a top feed, means for operating said feeds, a presser 15 finger coöperating with said top feed, and means for operating it.

46. In a sewing machine the combination of stitching mechanism, feeding mechanism comprising an underfeed constructed to receive a rib of the work and feed the work at 20 both sides of the rib, a throat plate constructed to permit the passage of the rib of the work from end to end thereof and to receive both sides of the work, a top feed, 25 means for operating said feeds, a presser finger coöperating with said top feed, means for operating it, means for lifting said top feed and presser finger and means coöperating therewith for pulling off additional 30 thread on the lifting of said top feed and presser finger.

47. In a sewing machine the combination of stitching mechanism, feeding mechanism

comprising an underfeed constructed to receive a rib of the work and feed the work 35 at both sides of the rib, a throat plate constructed to permit the passage of the rib of the work from end to end thereof and to receive both sides of the work, a top feed, means for operating said feeds, and means 40 for guiding the work and comprising a manually operated shiftable roller.

48. In a sewing machine the combination with stitching mechanism, of feeding mechanism comprising an underfeed consisting of 45 a feed dog having a slot for the reception of a work rib projecting at an angle to the side portions of the work, and a pair of feeding portions at opposite sides of said slot for feeding the work at opposite sides 50 of the rib.

49. In a sewing machine the combination with stitching mechanism, of feeding mechanism comprising a feed consisting of a feed dog having a slot for the reception of a 55 work rib projecting at an angle to the side portions of the work, a pair of feeding portions at opposite sides of said slot for feeding the work at opposite sides of the rib, and a throat plate in position to support 60 and guide the work, said throat plate having a slot extending from end to end thereof.

Signed at Nyack, in the county of Rockland and State of New York this 31st day of July, 1916.

JOHN P. WEIS.
